BROOM

Justus R. Kinney, Boston, Mass.

Application June 21, 1937, Serial No. 149,342

10 Claims. (Cl. 15—160)

This invention relates to brooms and particularly to brooms adapted for use in sweeping streets, stables, halls, lawns and similar surfaces, and the principal object of the invention is to produce a very durable broom which will be very effective in operation and will thoroughly clean any surface on which it is used.

The invention consists of a head formed of two metal members secured together and between which are secured the upper ends of a plurality of flat plates of spring metal, the lower ends of said plates having upwardly extending slits therein forming a plurality of spring fingers.

The object of the invention is attained by the structure of broom illustrated in the accompanying drawing.

For the purpose of illustrating the invention, one preferred form thereof is illustrated in the drawing, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawing—

Figure 1 represents a front elevation of a broom embodying the principles of the present invention, a portion of the front plate of the head being broken away.

Figure 2 represents a perspective of one of the slotted plates of spring metal to be secured to the broom head and showing one finger thereof curved to the rear into the position the fingers will assume when the broom is in use.

Figure 3 represents a horizontal section of the broom, on line 3, 3 of Fig. 1.

Figure 4 represents a vertical section of the broom, on line 4, 4 on Fig. 1 and Figure 5 represents a vertical section of the broom on line 4, 4 on Fig. 1 and showing the handle and upper portion of the head at an angle to the lower part of the head and the slotted plates secured thereto, thereby forming a push broom.

Similar characters indicate like parts throughout the several figures of the drawing.

In the drawing, 10 and 11 are two parallel metal members adapted to be riveted together by rivets 12 to form the head of a broom.

Each member is provided in the center thereof with an outwardly extending curved portion 13 adapted to form a socket to receive the lower

end of a handle 14 which may be of any well known construction.

This handle is secured to the head members 10, 11 by means of a pin 15.

Preferably the socket formed by means of the curved portions 13 is tapered as indicated in Figs. 1 and 4 of the drawing.

Between the lower ends of the metal members 10, 11 forming the head of the broom are disposed the upper portions of a plurality of thin flat plates 16 of spring metal.

These plates 16 may be disposed between the head members 10, 11 in one or more rows, the plates 16 in each row being aligned.

Each plate 16 is divided as indicated at 17 the divisions, extending upwardly from the bottom to a point near the top thereof, thereby forming a plurality of flat spring fingers 18 with their side edges in contact.

Normally these fingers 18 are straight from end to end with their faces aligned with the faces of the upper portion 19 of each plate as shown at the left of Fig. 2 of the drawing.

When however the broom is in use these spring fingers 17 will be curved rearwardly as indicated at 20 in Fig. 2 of the drawing.

For very light work, as for instance sweeping a lawn, a single row of these plates 16 is sufficient to accomplish the desired result.

For a little heavier work it is preferable to dispose two rows of plates 16 between the metal head members 10, 11, as indicated in Fig. 3 of the drawing.

Where heavier work is to be accomplished a greater number of rows of plates 16 may be used, as indicated in Fig. 4 of the drawing.

The upper portion 19 of each plate 16 is provided with two holes 21, said holes being adapted to receive rivets 22 by which the plates may be secured to the head of the broom.

The rivets 22 are equally spaced apart so that when several plates 16 are aligned and disposed between the head members 10, 11, the edges of the adjacent plates 16 will abut each other, as shown in Fig. 1 of the drawing.

In Fig. 1 of the drawing five aligned plates 16 are shown but if it is desired to use a smaller number of plates 16 in the head, as for instance three, the opposite ends of the metal members 10, 11 may be cut off along the lines *a* and *b*.

By this means of properly spacing the rivets apart in the head members 10, 11, and spacing apart the holes 21 in a similar manner, any number of plates 16 may be used in a row from one

to five by simply cutting off the opposite ends of the members 10, 11 as previously described.

Where only two of these plates 16 are shown in a row the contacting edges of the two members 16 will be alined with the axis of the handle 14.

When two rows of plates 16 are used the rear fingers will bear against the back faces of the fingers of the front row and stiffen the same when 10 the broom is in use.

A further stiffening of the front fingers will be obtained by using additional rows of plates, as indicated in Fig. 4 of the drawing.

Where ordinary light sweeping is to be done 15 by the broom it is preferable to have the handle 14 in the same plane as the head members 10 and 11.

Where several rows of plates 16 are used it is 20 preferable to have the upper ends of the head members 10, 11 bent rearwardly at an angle to the lower parts of the head members, as indicated in Fig. 5, thus forming a very effective push broom which may be used for certain kinds of work where the broom shown in Fig. 4 could not 25 be utilized to advantage.

This angularity of the handle 14 relatively to the lower part of the head members 10, 11 and the plates 16 interposed between and riveted to said head members makes it possible to push the 30 broom, this being quite essential when heavy street work is being done.

It is obvious, that by means of the construction herein shown, brooms may be made with flat spring fingers adapted for various conditions of 35 work.

These brooms may be made in the manner described either for use in the house, on lawns, for stables, or sweeping and cleaning streets, and various other purposes.

40 It is believed that the operation and many advantages of the invention will be understood without further description.

Having thus described my invention, I claim:

1. In a broom or similar device consisting of 45 a head having depending therefrom a plurality of rows of thin flat plates of spring metal, the upper ends of which are secured to said head and each plate having its lower portion divided into a plurality of straight flat-faced spring fingers in straight lines extending transversely of said head with the edges of adjacent fingers in contact.

2. In a broom or similar device consisting of 55 a head, a plurality of rows of flat plates of thin spring metal, the upper portions of said plates being secured to said head, each plate having its lower portion divided into a plurality of straight flat-faced spring fingers with the side edges of adjacent fingers in contact, the fingers 60 in the various plates being disposed in straight lines extending transversely of said head.

3. A sweeping implement comprising two similar metal members riveted together at their upper ends; a flat plate of spring metal secured 65 between the lower ends of said members and extending downwardly therefrom, the lower end of said plate having integral therewith a plurality of straight downwardly extending fingers with the side edges of adjacent fingers contacting and the lower ends of said fingers alined with the upper end of the plate.

4. A sweeping device having a head consisting of two similar metal members riveted together at their upper ends; a plurality of flat plates of 70 spring metal alined in a row with their upper

ends secured between said members, the side edges of said plates abutting each other, each plate having integral therewith a plurality of straight spring fingers with the side edges of adjacent fingers contacting and the lower ends of said fingers alined with the upper ends of said plates.

5. A sweeping device having a head consisting of two similar metal members riveted together at their upper ends; a plurality of flat plates 10 of spring metal alined in a row with their upper ends secured between said members, the side edges of said plates abutting each other, each plate having integral therewith a plurality of straight spring fingers with the side edges of 15 adjacent fingers contacting and the lower ends of said fingers alined with the upper ends of said plates and an operating handle secured to and extending from said head.

6. In a broom or similar device consisting of 20 a head comprising two similar metal members riveted together in parallelism; a flat plate of spring metal of which the upper end is interposed between the lower ends of said members and riveted thereto, said plate having at its lower 25 end and integral therewith a plurality of straight flat-faced spring fingers with the side edges of adjacent fingers contacting and the lower ends of said fingers alined with the upper ends of said plate, the length of each finger being substantially 30 fifteen times greater than the width thereof.

7. In a broom or similar device consisting of a head comprising two similar metal members riveted together in parallelism; a row of flat abutting plates of spring metal in alinement and having 35 their upper ends interposed between said members; and independent means for securing said plates to the lower ends of said members, each plate having at its lower end and integral therewith a plurality of straight flat-faced spring 40 fingers with their side edges contacting and their lower ends alined with the upper end of said plate.

8. In a broom or similar device consisting of a head comprising two similar metal members riveted together in parallelism; a plurality of 45 rows of flat plates of spring metal with adjacent faces in contact with each other, the upper ends of said plates being interposed between the lower ends of said members and secured thereto, each plate having at its lower end and integral therewith a plurality of straight flat-faced spring 50 fingers, the fingers in the various plates being disposed in straight lines extending transversely of said head.

9. In a broom or similar device consisting of 55 a head having depending therefrom a plurality of rows of flat plates of spring metal, the upper ends of which are secured to said head and each plate having at the bottom thereof a plurality of straight flat-faced spring fingers in straight 60 lines extending transversely of said head.

10. A sweeping implement comprising two similar metal members riveted together at their upper ends and provided with means for attachment thereof to an actuating element; a flat plate of spring metal secured between the lower ends of said members and extending downwardly 65 therefrom, the lower end of said plate having integral therewith a plurality of straight downwardly extending fingers with the side edges of adjacent fingers contacting and the lower ends of said fingers alined with the upper end of the plate.
